(57) **CLAIM**

The ornamental design for video game console cooling
mechanism, as shown and described.

DESCRIPTION

FIG. 1 is a perspective view of a video game console cooling
mechanism showing our new design;

FIG. 2 is a front elevational view thereof;

FIG. 3 is a top plan view thereof;

FIG. 4 is a left side elevational view thereof;

FIG. 5 is a perspective view of a second embodiment of FIG.
1;

FIG. 6 is a front elevational view thereof;

FIG. 7 is a top plan view thereof; and,

FIG. 8 is a left side elevational view thereof.

The broken lines are for illustrative purpose only and form
no part of the claimed design.

1 Claim, 8 Drawing Sheets

FIG. 1

FIG. 2
